VESSEL

Original Filed Jan. 20, 1930

UNITED STATES PATENT OFFICE

ERIC H. EWERTZ, OF ELIZABETH, NEW JERSEY

VESSEL

Application filed January 20, 1930, Serial No. 421,882. Renewed January 15, 1931.

This invention relates to an improved vessel of the barge type and has for its object to provide a vessel, the hull of which is constructed in its entirety of flanged metal plates, preferably electrically welded together to form an integral structure which will be very light and strong and at the same time inexpensive to construct.

Another object of the invention is to provide a vessel having in addition to the longitudinal and transverse bulkheads, a double bottom and double sides in order that a better protection may be provided for the cargo that is carried, the inner shell which forms the inner bottom and sides embodying therein reversely bent or U-shaped plates having flat intermediate portions, and said U-shaped plates being spaced at regular intervals throughout the interior of the outer shell and welded thereto at their outer edges in a manner to constitute U-shaped ribs, the spaces between said ribs being bridged by other plates which may be either plain or flanged, and which are preferably welded to the U-shaped plates adjacent to the flat intermediate portion thereof in a manner to form a continuous inner surface.

The invention consists in a vessel constructed as hereinafter described and particularly as set forth in the claims.

Referring to the drawings:

Figure 1 is a plan view of a vessel embodying my invention, a portion thereof being broken away and illustrated in section.

Fig. 2 is a sectional elevation taken on the line 2-2 of Fig. 1.

Fig. 3 is a detail horizontal section taken on the line 3-3 of Fig. 2.

Fig. 4 is a detail vertical section taken on the line 4-4 of Fig. 2.

Figs. 5 and 6 are sectional views illustrating modified embodiments of the invention.

Like numerals refer to like parts throughout the several views of the drawings.

In the drawings, 10 represents the outer shell of a vessel consisting of a plurality of plates 11, each having a flange 12 at one edge thereof extending inwardly. The side of the flange abuts against the flangeless edge of the adjacent plate and the two are fas-

tened together to make a water-tight joint by electric welding.

The plates 11 extend along the sides and the bottom of the vessel and the adjacent ends of successive plates where they abut together are welded so that, in effect, each plate is continuous and extends from the bow to the stern of the vessel.

The interior of the outer shell 10 is divided into a plurality of compartments 13 by means of a plurality of longitudinal bulkheads 14 and transverse bulkheads 15, and said bulkheads are strengthened and given added rigidity by means of vertical angle plates 16, which are welded to the bulkheads.

Located within the outer shell 10 is an inner shell 17, the latter being spaced a suitable distance apart from the side portion of the outer shell to form an inner side wall 18, and also being spaced a suitable distance above the bottom of the outer shell to form an inner bottom 19.

The inner side wall 18 embodies therein a plurality of vertical U-shaped plates 20 which extend from the bottom of the outer shell 10 to the deck of the vessel and said U-shaped plates are spaced apart at regular intervals along the entire inner surface of the outer shell 10. The inner shell 17 also embodies therein a plurality of horizontal U-shaped plates 21 which extend transversely across the vessel between the inner side walls 18 thereof and said plates are spaced apart at regular intervals along the entire inner bottom surface of the outer shell 10.

The U-shaped plates 20 embody therein a flat intermediate portion 22 which extends parallel with the side portion of the outer shell 10, and parallel side portions 23, the outer edges of which are welded at 24 to the outer shell 10. The flat intermediate portions 22 of the U-shaped plates 20 are connected together to form a continuous surface by means of connecting plates 25 which bridge the space between the adjacent U-shaped plates 20 and are welded at their opposite side edges at 26 to the corner portions of the U-shaped plates, see Fig. 3.

The U-shaped plates 21 embody therein a flat intermediate portion 27 and parallel side

portions 28, the outer edges of which are welded at 29 to the outer shell 10. The flat intermediate portions 27 of the U-shaped plates 21 are connected together to form a continuous surface by means of connecting plates 30 which bridge the space between the adjacent U-shaped plates 21 and are welded at their opposite side edges at 31 to the corner portions of the U-shaped plates 21, see Fig. 4.

The U-shaped plates 20 and 21, in effect, constitute ribs and act to stiffen the hull and produce a very rigid and strong construction, and at the same time the intermediate portions of the U-shaped plates 20 and 21 constitute portions of the inner side and bottom respectively of the inner shell 17.

The deck portion of the vessel may be constructed in any suitable manner, but preferably it is constructed of the same type of flanged plates that are employed in the construction of the outer shell 10, and these plates may be reinforced by any suitable form of flanged plate that may be desired.

In Fig. 5 I have illustrated a modified embodiment of my invention in which 32 constitutes a U-shaped plate having a flat intermediate portion 33 and parallel side portions 34. The spaces, however, between the U-shaped plates 32 are bridged by means of other U-shaped plates 35 also having flat intermediate portions 36 and parallel side flanges 37, the latter being adapted to rest against the side portions 34 of the U-shaped plates 32 and be secured thereto either by welding or riveting. The U-shaped plates 32 are secured to the outer shell 10 of the vessel in exactly the same manner as are the U-shaped plates 20 and 21 previously described, and the flat intermediate portions 33 and 36 of the plates 32 and 33 respectively co-operate to form a continuous surface constituting an inner shell for the vessel.

In Fig. 6 still another modified embodiment of the invention is illustrated in which 38 represents a U-shaped plate having a flat intermediate portion 39 and parallel side portions 40, the outer edges of which may be secured to the outer shell 10 of a vessel in exactly the same manner as are the U-shaped plates previously described. In this case, however, the U-shaped plates 38 are connected together and the spaces therebetween bridged by means of plates 41 which overlap the flat intermediate portions 39 of the U-shaped plates and are secured thereto either by welding as illustrated at 42, or by riveting as illustrated at 43. In this case also the flat intermediate portions 39 of the U-shaped plates and the plates 41 co-operate to form the inner shell of the vessel.

I claim:

1. A vessel, the outer shell of which embodies therein a plurality of metal plates and an inner shell comprising a plurality of reversely bent plates welded to the outer shell

and spaced apart thereon, and other plates welded to the reversely bent plates and co-operating therewith to form an integral structure and a continuous wall.

2. A vessel, the outer shell of which embodies therein a plurality of metal plates and an inner shell comprising a plurality of U-shaped plates fastened to the outer shell and spaced apart upon the interior thereof, and other plates secured to and bridging the spaces between said U-shaped plates and co-operating therewith to form a continuous inner wall.

3. A vessel, the outer shell of which embodies therein a plurality of metal plates and an inner shell embodying therein a plurality of U-shaped plates fastened at their outer edges to the outer shell and positioned along the interior thereof, each of said U-shaped plates having a flat intermediate portion, and other plates resting upon and secured to said U-shaped plates and forming a continuation of the intermediate portion thereof.

4. A vessel, the outer shell of which embodies therein a plurality of metal plates, an inner shell embodying therein a plurality of U-shaped plates fastened at their outer edges to the outer shell and positioned at intervals along the interior thereof, each of said U-shaped plates having a flat intermediate portion, and other plates secured to the U-shaped plates and bridging the spaces therebetween, said last-named plates co-operating with the intermediate portions of the U-shaped plates to render the inner shell continuous.

5. A vessel, the outer shell of which embodies therein a plurality of metal plates and an inner shell embodying therein a plurality of U-shaped plates welded at their outer edges to the outer shell and spaced apart upon the interior thereof, each of said U-shaped plates having a flat intermediate portion, and other plates welded to the corner portions of the U-shaped plates and bridging the spaces therebetween and co-operating therewith to render the inner shell continuous.

In testimony whereof I have hereunto set my hand.

ERIC H. EWERTZ.
